Patented Nov. 18, 1913.

UNITED STATES PATENT OFFICE.

ELBERT J. HALL, OF WEST BERKELEY, CALIFORNIA.

INTERNAL-COMBUSTION ENGINE.

1,078,919.

Specification of Letters Patent. Patent No. 1,078,919.

Application filed June 13, 1911. Serial No. 632,919.

To all whom it may concern:

Be it known that I, ELBERT J. HALL, a citizen of the United States, and a resident of West Berkeley, in the county of Alameda and the State of California, have invented certain new and useful Improvements in Internal-Combustion Engines, of which the following is a specification.

The invention relates to improvements in internal combustion engines in which a carbureter is used to volatilize the hydrocarbons before they are fed into the engine cylinders and has special reference to improvements in the oiling system and carburation.

15 The object of the invention is to increase the efficiency of the engine by warming the carbureter and thereby obtaining a more thorough vaporization of the hydrocarbons, by means of the lubricating oil used in the engine and at the same time lowering the temperature of the oil.

During the operation of the carbureter, the heat absorbed by the volatilizing hydrocarbons reduces the temperature of the carbureter to such a low degree, that frost often appears on the outer surface of the carbureter and the feed pipes. When such conditions obtain it is evident that the hydrocarbons will not volatilize as readily as if there were sufficient heat to be absorbed and consequently the hydrocarbons either enter the engine partly in the vapor state or a sufficient supply cannot be obtained. The oil used in lubricating the bearings and cylinders in the engine becomes heated to a high degree during the operation of the engine and causes the engine to become excessively heated which produces many disadvantages.

40 By the use of the improvement of my present invention, however, these disadvantages are overcome and a more efficient operation is obtained. The heated oil from the crank case of the engine is circulated around the carbureter or the manifold thereby cooling the oil and warming the carbureter. The cooled oil is then conveyed back to the engine and is distributed over the various parts thereof.

45 With these and other objects in view, as will more fully hereinafter appear, the invention consists in certain novel features of construction and arrangement of parts hereinafter fully described, illustrated in the accompanying drawing and pointed out in

the appended claims, it being understood that various changes in construction and arrangement of the structure may be made without departing from the spirit or sacrificing any of the advantages of the invention.

The drawing shows an end view of an internal combustion engine embodying the improvements of my invention, parts of the structure being broken away to disclose the construction.

The engine may be a multi-cylinder engine of the type illustrated with the cylinders 2 set at an angle of 90° to each other, or it may be of any other construction. The 70 pistons transfer their motion to the crank shaft 3 which is located in the crank casing 4. Within the casing 4 and preferably situated above the crank shaft 3 is the cam-shaft 5 which operates the valves and ignition devices. The carbureter 6 is placed in any desired position and is connected to the cylinders 2 by the conductors 7.

A receptacle or reservoir 8 is located below the crank case 4 which is provided with 80 apertures 9 to allow the oil to flow from the crank case into the reservoir. The lower part of the crank case 4 is preferably formed semi-circular in cross section and the apertures 9 are located above the lowest part of the bottom, so that a quantity of oil will remain in the case to assist in lubricating the parts by the splash system.

Connected to the reservoir 8 by the conductor 12 is an oil pump 13 which draws the oil from the reservoir and forces it to the carbureter 6 through the conductor 14. The oil pump 13 may be of either the reciprocating or rotary type, and in the drawings I have illustrated a pump of the reciprocating type which is operated from the crank shaft 3 through the eccentric 15 and the connecting rod 16. When a rotary pump is used it may be connected to the crank shaft by suitable gearing. I do not wish to limit myself however, to operating the pump from the crank shaft as it may be operated with equal efficiency from the cam-shaft 5 or from the other moving parts of the engine.

Surrounding the manifold 17 of the carbureter 6 is a fluid tight casing 18, inclosing a space surrounding the manifold. This casing 18 may surround more or less of the carbureter and supply pipes 7 as desired and I do not wish to be restricted to the ex-

act showing made by the drawing. The warm oil flowing in conductor 14 passes into the space surrounding the manifold 17, where it is cooled, transferring its heat to the manifold and thereby increasing the efficiency of the action of the carbureter. The cool oil passes out of the casing 18 through the conductor 19 which conveys it back to the crank case.

10 As a means of distributing the oil over the moving parts in the crank case, I prefer to use the hollow cam-shaft 5 which is provided with apertures 21 at the proper points to allow the oil to drop therefrom onto the surfaces to be lubricated. The conductor 19 is connected with the interior of the cam-shaft at one end and deposits the cool oil therein.

15 Other methods of distributing the cool oil may be employed and I do not desire to limit myself to the methods shown and described.

20 I claim:

1. The combination with an internal combustion engine having an oiling system and a carbureter of a closed conductor connected 25 at both ends with the engine and extending into close relation to said carbureter and means operated by the engine for circulating the oil through said conductor.

2. The combination with an internal combustion engine having an oiling system, and a carbureter, of a pump operative by the engine connected to said oiling system, a casing surrounding the carbureter, a conductor extending from the pump into said casing, and

35 a second conductor extending from the casing back to the oiling system.

3. The combination with an internal combustion engine and a carbureter partly surrounded by a fluid tight casing, of a lubricating oil reservoir on the crank case of the 40 engine adapted to receive oil from said crank case, a conductor connecting said reservoir with the casing surrounding the carbureter, a pump in said conductor arranged to be operated by the engine, and a conductor for 45 conducting the oil from the carbureter casing to the engine.

4. The combination with an internal combustion engine having a hollow apertured cam-shaft and a carbureter having a casing 50 surrounding the same, of a means for forcing the lubricating oil from the crank case of the engine through the casing surrounding the carbureter and into the hollow cam-shaft.

5. The combination with an internal combustion engine having an oiling system and a carbureter, of a pump connected to said oiling system adapted to be operated by the engine, a conductor extending from the 55 pump to the carbureter and adapted to convey the oil into thermal contact with the carbureter and a conductor for returning the oil to the engine.

ELBERT J. HALL.
